UNITED STATES PATENT OFFICE.

CLARENCE L. RICE AND TANNIE B. WILKINSON, OF LAUREL, MISSISSIPPI.

LUMBER-MARKING MACHINE.

Application filed October 5, 1925. Serial No. 60,554.

Our said invention relates to a device for marking the grade or other desired indicia upon lumber in accordance with the requirement of certain lumber manufacturing associations and it is an object of the invention to provide a device which will supply ink to a die member and subsequently embed the characters on the die in the wood to form the inked impression.

Heretofore it has been customary to affix characters to be impressed on the end of a handle much the same as a rubber stamp and after applying such characters to a pad saturated with ink the device was placed 10 against the article to be marked and struck a blow with a hammer to impress the characters onto said article. This operation was clumsy and required considerable care and skill in the performance of the same. Also 15 it was unhandy and burdensome to carry the tools necessary to perform the required operation.

Referring to the accompanying drawings which are made a part hereof and on which 20 similar reference characters indicate similar parts,

Figure 1 is a top plan view,

Figure 2, a central longitudinal vertical section,

Figure 3, a front end elevation with the inking pad removed,

Figure 4, a detail perspective of the end 30 of the die carrying head, and

Figure 5, a section on the line 5—5 of 35 Figure 2.

The device comprises a handle or body 10 having a longitudinal bore 11 forming a cylinder for the reception of a piston 12 carrying at its outer end a head 13 which supports a die member 14 for impressing suitable characters 15 on the article to be marked. The handle 10 is provided with a forwardly extending flattened portion 16 having an upwardly standing rim joined at its rear portion to the body 10 and having parallel arms 17 disposed in spaced relation to said body. The arms 17 are provided with longitudinally disposed slots 18 in which blocks 19 are slidably mounted, said blocks being seated in grooves 20 in the ends of the head 13 and held therein by means of screws 21. The die member is permitted therefore to reciprocate on its support until the operating end of the die member is slightly in advance of the flattened portion 16 and arms 17.

The rod supporting the piston 12 is pro-

vided at its forward end with a reduced extremity 22 having a shoulder formed about the same and the supporting head 13 for the die member 14 is provided with a recess 23 for the reception of said reduced portion. The parts may be fastened together in any desired manner as, for example, by a pin 24.

In order to securely fasten the die member on its support I provide transverse dovetail recesses 25 in the head 13 and co-operating dove-tails 26 in the die member 14. These co-operating parts are preferably tapered from top to bottom so that the die member will be maintained in proper position during operation. If desired the tapered feature may be omitted and the parts may be fastened together in any desired manner.

The forward end of the body 10 is provided with an upright arm 27 in the bifurcated extremity of which is pivoted the arm 28 of a frame 29 carrying an inking pad 30, said inking pad being provided with bosses 31 for engagement with screws 32 extending through the frame 29. The inking operation may be performed by swinging the pad 30 into position to engage the characters 15 on the die member 14 and in order to effect this operation between each reciprocation of the die member, we provide lugs 33 and 34 on the forward end of the piston rod and arm of the frame for the inking pad respectively, and pivotally connect said lugs by means of a link 35. On account of this construction the reciprocation of the piston and its supporting rod will cause the link 35 to advance and withdraw the inking pad from engagement with the characters on the die member.

In order to effect the operation of the piston I provide the rear end of the body 10 with a valve casing 36 having a passage 37 forming communication between the interior of the casing and the bore of the handle behind the piston. A valve seat 38 is formed in said casing against which a valve 39 is normally held by means of a spring 40, the outer end of which is seated in a removable plug 41 permitting access to the valve. The valve 39 is provided with a stem 42 extending through the casing and adapted to be depressed by a lever 43 pivotally mounted in a bifurcated arm 44 on said casing to unseat said valve. An air supply pipe 45 is connected to the end of the casing adjacent the spring 40 and air

pressure will assist in maintaining the valve on its seat. When the lever 43 is operated to unseat the valve, compressed air will force the piston 12 outwardly. In order to insure the return of the piston 12 to its retracted position, we provide a spring 46 adjacent each end of the support 13 for the die head and attach one end of each spring to an ear 47 on said support 13 and the other end of the spring 46 to an ear 48 on the rear portion of the flattened portion 16. The piston 12 is formed with a groove or bleeder passage 49 in its periphery to permit entrapped air to escape.

15. In operation when it is desired to stamp wood or kindred material, the forward end of the device is pressed against the same and the lever 43 is depressed, whereupon the compressed air will force the piston and its associated parts forward and link 35 will throw the inking pad out of the path of the characters which will be imbedded in the material operated upon. When the handle 43 is released the springs 46 will return the parts to initial position for repetition of the operation, the air behind the piston escaping through the bleeder passage.

It will be obvious to those skilled in the art that various changes may be made in our device without departing from the spirit of our invention, and we therefore do not limit ourselves to what is shown in the drawings and described in the specification but only as set forth in the appended claims.

35. Having thus fully described our said invention, what we claim as new and desire to secure by Letters Patent is:

1. A portable stamping device comprising a body, a rod mounted in said body, a die member on the forward end of said rod, a piston on the rear end of said rod, means for admitting compressed fluid to said piston for forcing the same longitudinally of said body, and a spring having one end connected to said die member and its other end connected to said body whereby when the die member is forced forwardly the spring will return the same to its initial position, substantially as set forth.

50. 2. A portable stamping device comprising a hollow body having an integrally formed forwardly extending portion with parallel slotted arms, a die head having its ends disposed within the slots in said arms, a piston in said hollow body, a rod connecting said piston and die head, and means for admitting compressed fluid to said piston for forcing the same longitudinally of said body, substantially as set forth.

60. 3. A portable stamping device comprising a hollow body having an integrally formed forwardly extending portion with parallel slotted arms, a die head having its ends disposed within the slots in said arms, a pis-

ton in said hollow body, a rod connecting said piston and die head, means for admitting compressed fluid to said piston for forcing the same longitudinally of said body, and a spring having one end connected to said die member and its other end connected to said body whereby when the die member is forced forwardly the spring will return the same to its initial position, substantially as set forth.

4. A stamping device comprising a hollow body having a forwardly extending portion with parallel slotted arms, a die head having its ends disposed within the slots in said arms, a piston in said hollow body, a rod connecting said piston and die head, means for admitting compressed fluid to said piston for forcing the same longitudinally of said body, and a spring having one end connected to said die member and its other end connected to said body whereby when the die member is forced forwardly the spring will return the same to its initial position, said piston having a bleeder passage permitting escape of fluid entrapped therebehind, substantially as set forth.

5. A stamping device comprising a body, a rod mounted in said body, a die member on the forward end of said rod, a piston on the rear end of said rod, means for admitting compressed fluid to said piston for forcing the same longitudinally of said body, and means for inking said die member comprising an inking pad pivoted on said body and having a link pivotally connecting said pad and said rod whereby when the rod is moved outwardly the inking pad will be retracted and when moved in a reverse direction the pad will be moved toward said die member, substantially as set forth.

6. A stamping device comprising a hollow body having a forwardly extending portion with parallel slotted arms, a die head having its ends disposed between the slots in said arms, a piston on the rear end of said rod, means for admitting compressed fluid to said piston for forcing the same longitudinally of said body, and means for inking said die member comprising an inking pad pivoted on said body and having a link pivotally connecting said pad and said rod whereby when the rod is moved outwardly the inking pad will be retracted and when moved in a reverse direction the pad will be moved toward said die member, substantially as set forth.

7. In a stamping device, a handle having a longitudinally disposed cylindrical bore, a piston in said bore, a piston rod having one end connected to said piston and having its other end extending outwardly beyond the end of the bore, a cross-head on said piston, a spring disposed longitudinally of and on each side of said handle having one

end connected to the handle and its other end connected to the cross-head, substantially as set forth.

8. In a stamping device adapted to be operated in a horizontal position, a reciprocating cross-head having tapered transverse dove-tail recesses in its forward face and a die member mounted on said cross-head, said die member having tapered transversely disposed dove-tail projections on its rear face corresponding to the recesses in the cross head, substantially as set forth.

9. A fluid operated stamping device comprising a hollow handle, a piston in said hollow handle having a die member supported on its forward end, a bracket on said handle, an ink pad pivoted on said bracket, a bracket on the forward end of the piston and a link pivoted to the bracket on the piston and to the ink pad whereby when the die member is operated the link will throw the ink pad into and out of the path of movement of the die member, substantially as set forth.

10. A stamping device comprising a hollow handle, a rod mounted in said hollow handle, a die member supported on the forward end of the rod, a piston on the rear end of the rod, an inlet for admitting an actuating medium into said hollow handle for forcing

ing the piston outwardly in the handle, 30 means for controlling the flow of the actuating medium through said inlet, spring means for retracting the piston, said piston having a bleeder passage permitting escape of entrapped fluid, substantially as set forth. 35

11. An air operated hand stamp comprising a hollow handle having a forwardly extending portion with arms extending outwardly and forwardly from opposite sides of said handle, a rod in said hollow handle, 40 having its rear end shaped to conform to the interior of the handle and forming a piston and having its opposite end extending out of the hollow handle and provided with a die member supported thereon and guided 45 by said arms, means for admitting compressed fluid to the piston for operating the die member and spring means disposed longitudinally of the handle and connected at one end to the handle and at the opposite 50 end to the die member for retracting the same, substantially as set forth.

In witness whereof, we have hereunto set our hands at Laurel, Mississippi, this 26th day of September, A. D. nineteen hundred and twenty-five.

CLARENCE L. RICE.
TANNIE B. WILKINSON.
